(57) **CLAIM**

The ornamental design for a cart for folding chairs and tables, as shown and described.

DESCRIPTION

FIG. 1 is a perspective view of a cart for folding chairs and tables in an expanded configuration showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of a cart for folding chairs and tables in a retracted configuration showing my new design;

FIG. 9 is a front elevation view thereof;

FIG. 10 is a rear elevation view thereof;

FIG. 11 is a left side elevation view thereof;

FIG. 12 is a right side elevation view thereof; and,

FIG. 13 is a top plan view thereof.

The broken lines adjacent to the edge of the cart in FIG. 7 are for the purpose of illustrating portions of the cart for folding chairs and tables and form no part of the claimed design. The broken lines showing a set of wheels and a hinge in the figures are for the purpose of illustrating environment and form no part of the claimed design.
